UNITED STATES PATENT OFFICE.

ALEXANDER MITCHELL, OF WILKES-BARRÉ, PENNSYLVANIA.

LOCOMOTIVE SPARK-ARRESTER.

SPECIFICATION forming part of Letters Patent No. 251,621, dated December 27, 1881.

Application filed September 19, 1881. (No model.)

To all whom it may concern:

Be it known that I, ALEXANDER MITCHELL, a citizen of the United States, residing in Wilkes-Barré, Luzerne county, Pennsylvania, 5 have invented certain Improvements in Locomotive Spark-Arresters, of which the following is a specification.

My invention relates to an improvement in that class of spark-arresters which have screens 10 for preventing the admission of large sparks or particles of ignited fuel to the stack, the object of my invention being to provide effective means for disposing of these large sparks and preventing their accumulation in the smoke- 15 box of the engine.

In the accompanying drawings, Figure 1, Sheet 1, is a transverse section of the smoke-box of a locomotive, illustrating my invention; Fig. 2, a sectional plan on the line 1 2, Fig. 1, 20 and Figs. 3 and 4 views on a smaller scale than Fig. 1, illustrating modifications of the invention.

In Figs. 1 and 2, A represents the smoke-box section of the boiler; B, the front tube-sheet; D, the smoke-stack, and E the usual duplex exhaust-nozzle. A screen, F, is secured at its lower end to the nozzle E, the upper end of the screen being secured to the shell of the boiler, so that sparks and ignited particles of 25 fuel must pass through the screen before they can gain access to the stack D, all particles which are too large to pass through the meshes of the screen falling into the bottom of the smoke-box. From this portion of the smoke- 30 box to the screen F, at a point some distance above the lower end of the latter, extends a lift-pipe, G, having at the upper end lateral branches H H, which communicate with external boxes or receptacles, J, on opposite sides of 35 the smoke-box. The upper end of each of these receptacles J communicates, through a pipe or pipes, a, with the interior of the stack D, the end of each pipe a being turned upward within the stack, so that the draft through the 40 latter will induce a draft through the pipes a from the receptacles J. Within each of the receptacles J is a screen, b, interposed between the mouth of the pipe a and that of the branch H of the lift-pipe, and said receptacles are 45 provided with nozzles d, through which jets of water or steam can be projected into the same,

these jets, being under the control of the engineer, and suitable drip-valves, e, being provided for preventing the rising of the water or condensed steam in the receptacles to such a 55 height as would permit it to flow through the branches H of the lift-pipe into the smoke-box of the boiler.

The operation of the device is as follows: The large sparks and particles of ignited fuel which 60 drop into the bottom of the smoke-box are caused to rise in the lift-tube G, owing to the upward draft caused by the blasts of steam from the nozzle E and by the induced draft through the pipes a of the receptacles J. Some 65 of the particles may be broken by contact with the lower portion of the screen D, and pass through the meshes of said screen, and thence directly to the stack; but the large particles pass upward through the branches H of the 70 lift-pipe and enter the receptacles J, in which they are deposited, the screens b preventing them from entering the stack through the pipes a. The sparks are extinguished by the 75 jets of water or steam from the nozzles d, and are discharged from the receptacles at intervals, the bottoms of the receptacles being pivoted as shown in Fig. 1, or being provided with suitable valved discharge-pipes, in order to facilitate the emptying of the same. By 80 this means the smoke-box is kept clean at all times, the ready escape of the large particles from the latter being provided for, so that said particles are not likely to adhere to and clog the meshes of the screen F, as usual, the draft 85 of the engine being thus unobstructed, and the steaming qualities of the engine not being interfered with.

Various forms of exhaust-nozzles and screens may be used in connection with the lift-pipe 90 and receptacles in carrying out my invention. For instance, instead of the low nozzle and inverted conical screen shown in Fig. 1, I have illustrated in Fig. 3 a high nozzle and a cylindrical or box screen in the upper portion of 95 the smoke-box, and in Fig. 4 I have shown a horizontal screen similarly located.

In Fig. 4, also, I have shown two lift-pipes instead of the single lift-pipe with two branches, one pipe being arranged in front and the other 100 in the rear of the exhaust-nozzle.

I am aware that sparks have been blown from

the bottom of the smoke-box onto the ground and into receptacles below said smoke-box, but in such cases the exhaust-nozzles must be furnished with jet-pipes to induce draft through 5 the spark-conveying pipes. By locating the spark-receptacle above the bottom of the smoke-box I am enabled to dispense with these jet-pipes, the draft of the stack and that induced by the blast from the exhaust-nozzles being 10 sufficient to induce the passage of the sparks from the bottom of the smoke-box into the receptacle.

I claim as my invention—

1. The combination of the smoke-box and 15 its stack, the exhaust-nozzle, the spark-arresting screen in the smoke box, a spark-receptacle located above the bottom of the smoke-box, and a lift-pipe communicating with the upper end of the receptacle and with the bottom of 20 the smoke-box, as set forth.

2. The combination of the smoke-box and its stack, the exhaust-nozzle, the spark-arresting screen in the smoke-box, a spark-receptacle located above the bottom of the smoke-box, 25 and a lift-pipe surrounding the exhaust-nozzle, and having a branch communicating with the upper portion of said spark-receptacle, as specified.

3. The combination of the smoke-box and its

stack, the exhaust-nozzle, a spark-receptacle, 30 a lift-pipe having a branch communicating with said spark-receptacle, a screen extending from the lift-pipe to the shell of the smoke-box, and a screen extending to the exhaust-nozzle from the inside of the lift-pipe, above 35 the branch of the same, as set forth.

4. The combination of the smoke-box and its stack, a spark-arresting screen, a spark-receptacle above the bottom of the smoke-box, a lift-pipe communicating with the bottom of 40 the smoke-box and the upper portion of the spark-receptacle, a draft-pipe, *a*, and a screen, *b*, interposed between the pipe *a* and the lift-pipe, and occupying such relation to the latter that the sparks impinge upon the screen as 45 they emerge from the lift-pipe, as set forth.

5. The combination of the smoke-box, its spark-arresting screen and stack, the lift-pipe, and a spark-receptacle having a draft-pipe, *a*, a screen, *b*, a nozzle, *d*, and an overflow, *e*, as 50 set forth.

In testimony whereof I have signed my name to this specification in the presence of two subscribing witnesses.

ALEXANDER MITCHELL.
